EDWARD N. JACOBI, OF MILWAUKEE, WISCONSIN, ASSIGNOR TO EDWARD N. JACOBI,
TRUSTEE, OF MILWAUKEE, WISCONSIN

AUTOMATIC LIGHTER FOR BURNERS

Application filed June 24, 1929. Serial No. 373,357.

This invention relates to automatic lighters for burners and, though designed for lighting the burners of a gas range or the like and depending on the variation in pressure in the supply pipe incident to the opening of the burner valve, is not confined thereto.

An object of the invention is to simplify the construction of such automatic lighter mechanism, making it inexpensive to manufacture.

With the above and other objects in view the invention consists in the automatic lighter for burners as herein claimed and all equivalents.

Referring to the accompanying drawings, in which like characters of reference indicate the same parts in different views,

Fig. 1 is a central sectional view of an automatic lighter for burners constructed in accordance with this invention, the valve thereof being in the closed or normal position;

Fig. 2 is a similar view with the valve in the open position caused by the opening of a burner valve reducing the pressure in the supply pipe, and

Fig. 3 is a plan view showing the usual relation of the lighter to the burner.

In these drawings, 10 indicates a gas supply pipe or manifold, which, in the case of a gas range, supplies a plurality of burners 11 controlled individually by their valves 12.

A casing 13 has a threaded connection 14 with the supply pipe 10 and is provided with a cup-shaped cover member 15 with a gasketed diaphragm 16 between them, said diaphragm dividing the casing and its cover into a lower pressure chamber 17 and an upper counter pressure chamber 18. Between these two chambers there is restricted open passage afforded by a passageway 19 in the cover member controlled by a needle valve 20 and communicating through registering openings in

the diaphragm and its gaskets with a passageway 21 in the casing member. A valve seat 22 formed in the casing member 13 has a pipe 23 connecting it with a pilot 24 in which there is normally maintained a low pilot flame which develops into radiating jets

of burner-lighting flame extending to the burners 11 upon the opening of an automatic valve admitting greater gas pressure thereto.

A set screw 25 is threaded through the casing 13 into the pressure chamber 17 so as to be capable of adjustment, with a lock nut 26 thereon for maintaining its adjustment. Within the chamber 17 a yoked member 27 is swiveled on the end of the screw 25 and forms the fulcrum for a valve lever 28 having a conical pilot flashing valve member 29 pivotally mounted on one end and having a yoke at the other end with slot and pin connection to a stud 30 anchored to the center of the diaphragm 16. A coiled spring 31 has one end connected with a spring clip 32 swiveled on the anchor stud 30 and its other end engaged by the end of a screw 33 adjustably threaded through the cover member 15 and provided with a set nut 34 for locking it in its adjustment. The action of this spring is to hold the valve closed on its seat when the gas pressures above and below the diaphragm are equalized, which is the normal state owing to the communication through passageway 19, 21.

For maintaining the normal small pilot light there is a by-pass around the valve formed by a passageway 35 controlled by a needle valve 36.

In operation the opening of a burner valve 12 causes a reduction in pressure within the supply pipe 10 and therefore within the pressure chamber 17, but, owing to the limited capacity of the passageway 19, 21, the reduction in pressure in the chamber 18 is gradual and for a short time it exceeds the pressure in chamber 17 to flex the diaphragm 16 and cause the valve to open and admit a greater volume of gas to the pilot, causing it to flash or produce the radiating jets of lighting flame to light the burner of which the valve was opened. The lighting flame continues only momentarily, however, since the equalizing passageway 19, 21, permits the gas to flow therethrough from chamber 18 to chamber 17, thus permitting the spring to again close the valve and restore the parts to their normal positions ready for the next operation when a burner valve is opened.

The period of duration of the lighting flame may be varied by the adjustment of needle valve 20 and the proper adjustment of the valve and the spring may be made by adjusting screws 25 and 33 respectively.

The burner lighter of this invention is of simple, inexpensive construction but is durable and free from parts likely to require attention so as to render service indefinitely in the automatic lighting of burners whenever their valves are opened.

While, for convenience of illustration, the needle valves 20 and 36 are represented as diametrically opposite, it may be preferred to locate them otherwise, such as 90° apart.

What I claim as new and desire to secure by Letters Patent is:

1. A lighter for a burner having valve connection with a supply pipe, comprising a casing communicating with the supply pipe, a diaphragm in the casing dividing it into a pressure chamber and a counter-pressure chamber, there being a restricted communication between the two chambers, a pilot flashing valve operated by the diaphragm, and a pilot with its supply controlled by the pilot flashing valve.

2. A lighter for a burner having connection with a supply pipe, a pressure-sensitive diaphragm having both sides subjected to the pressure in the supply pipe, there being a restricted passageway for communicating pressure to one side of the diaphragm, a pilot flashing valve operated by the diaphragm, and a pilot with its supply controlled by the pilot flashing valve.

3. A burner lighter comprising a casing, a cover therefor, a diaphragm between the casing and cover dividing the interior into a pressure chamber and a counter-pressure chamber, a supply pipe connection for the pressure chamber, a pilot connection for the pressure chamber forming a valve seat, and a pilot flashing valve seated thereon, there being a restricted passage connecting the pressure chamber with the counter-pressure chamber.

4. A lighter for a burner having valve connection with a supply pipe, comprising a casing communicating with the supply pipe, a diaphragm dividing the casing into two pressure chambers, there being a restricted passage connecting said chambers, a spring-seated pilot flashing valve operated by the diaphragm, and a pilot having communication with the chamber controlled by the pilot flashing valve.

5. A lighter for a burner having valve connection with a supply pipe comprising a casing communicating with the supply pipe, a diaphragm therein dividing the casing into two pressure chambers, there being a restricted passageway connecting the chambers, an adjustable set screw in the casing, a pivot yoke swiveled thereon, a lever fulcrumed in

the yoke, a valve carried by the lever, a stud on the diaphragm engaging the lever, and a pilot with its supply controlled by the valve.

6. A lighter for a burner having valve connection with a supply pipe, comprising a casing having communication with the supply pipe, there being a valve seat in the casing, a pilot communicating therewith, a cup-shaped cover for the casing, a diaphragm mounted between the casing and the cover, a stud carried by the diaphragm, an adjusting screw threaded in the cover, a spring connecting the adjusting screw with the stud, an adjusting screw threaded in the casing, a lever having a fulcrum swiveled on said adjusting screw and having one end connected with the stud, a valve connected with the other end of the lever and seated on the valve seat, and valve-controlled passages connecting the spaces on opposite sides of the diaphragm and connecting the interior of the casing with the pilot connection respectively.

In testimony whereof I affix my signature.

EDWARD N. JACOBI.
